ANTIFREEZE TESTER

Alan G. Wallskog, Prospect Heights, Ill., assignor to
E. Edelmann & Co.

Filed Feb. 24, 1970, Ser. No. 21,592

Term of patent 14 years

Int. Cl. D10—11

U.S. Cl. D52—7

FIG. 1 is a perspective view of an antifreeze tester showing my new design;

FIG. 2 is a front elevational view;

FIG. 3 is a right side elevational view;

FIG. 4 is a rear elevational view;

FIG. 5 is a bottom plan view;

FIG. 6 is a top plan view; and

FIG. 7 is a fragmentary left side elevational view.

Portions of the dip tube are omitted from FIGS. 3, 5 and 6 for convenience of illustration.

I claim:

The ornamental design for an antifreeze tester, as shown and described.
